UNITED STATES PATENT OFFICE.

ROBERT L. HARPER, OF LORENA, TEXAS.

CULTIVATOR.

SPECIFICATION forming part of Letters Patent No. 770,575, dated September 20, 1904.

Application filed June 22, 1904. Serial No. 213,667. (No model.)

To all whom it may concern:

Be it known that I, ROBERT L. HARPER, a citizen of the United States, residing at Lorena, in the county of McLennan and State of Texas, have invented new and useful Improvements in Cultivators, of which the following is a specification.

This invention relates to cultivators, and more especially to an arch constituting a part thereof.

Cultivators ordinarily have an arched bar, the members or branches of which are connected with the beams of the cultivator and are shiftable relatively to each other in order to change the relation of the beams either toward or from each other.

It is the primary object of my invention to provide an arch that is simple in construction, efficient in action, and by the operation of the controlling member of which the beams can be readily spread or brought together to vary the transverse relation of the shovels. The controlling member in question is of such a character that a slight movement of the same will effect a considerable movement of the beams, and such operation can be accomplished while the cultivator is in motion and without the necessity of the driver or operator thereof leaving his seat.

In the drawings accompanying and forming a part of this specification I have illustrated one simple adaptation of the invention, which will be fully set forth in the following description; but I do not limit myself to the precise construction thus disclosed, for certain variations may be adopted within the scope of the claims succeeding said description.

Referring to said drawings, Figure 1 is a perspective view of an arch including my invention and showing the way it is associated with the beams of a cultivator, said beams and certain other parts of said cultivator being shown by dotted lines. Fig. 2 is an elevation of the arch detached. This figure also shows the seat-bars in transverse section.

Like characters designate like parts throughout both figures.

In Fig. 1 of the drawings I have illustrated by dotted outline a cultivator of well-known form, the same including in its make-up two

parallel beams, as 2, to which the usual shovels may be connected. The seat is represented by 3, and, as will hereinafter appear, the controlling or actuating member for the arch constituting the subject-matter of the present application is within easy reach of the driver occupying said seat, whereby the adjustment of the beams 2 toward or from each other can be readily secured without the necessity of the driver dismounting and while the cultivator is in action.

The arch consists of two substantially similar or complementary bars, as 4, jointed or hinged together at their upper ends in any desirable way. The two bars diverge away from each other toward their lower ends to present a structure that is approximately of inverted-V form. The lower ends of said bars are equipped with studs or pins, as 5, adapted to be fitted into sockets on the beams 2 and to be permanently held in place in any desirable manner. Below the joint or hinge between the coöperating bars 4, in practice generally about eight inches, is horizontally disposed an elongated loop-shaped nut or turnbuckle 6, the end bars of which are internally left and right threaded to engage the inner ends of the rods 7, the outer ends of said rods being connected with the bars 4 in any desirable way.

It will be obvious that upon turning the nut or turnbuckle 6 in one direction the bars 4 will be equally spread and that by turning them a similar distance in the opposite direction they will be drawn together an equal extent. In practice the turnbuckle or nut 6 will be within ready access of the driver occupying the seat 3, so that he can, as previously indicated, without leaving his seat and while the cultivator is being moved forward, by the simple manipulation of the turnbuckle in either direction, operate the bars 4 through the intermediate rods 7, and thereby the beams 2, to adjust or regulate the distance between the shovels. The turnbuckle or right and left threaded nut 6 will be so situated in proximity to the hinge between the two coöperating bars 4 and the pitch of the engaging threads of the nut or turnbuckle 6 and the rod 7 will be such that a slight motion of the said turnbuckle will secure an effective or desirable

motion of the beams through the intervening connections. For example, in practice I intend to so proportion the parts that one half-rotation of the turnbuckle will be sufficient 5 to move the beams toward or from each other a distance equaling one inch. It will be apparent, therefore, that I am enabled to secure with rapidity and facility large and small adjustments of the shovels relatively to each 10 other and that I am enabled to maintain them in locked lateral relation without the necessity of employing independent or extraneous locking means, as is ordinarily the case. In other words, the turnbuckle or nut 6 constitutes simultaneously an actuating or controlling device and a locking device.

It will be seen that the seat 3, hereinbefore mentioned, is shown as connected to the outer ends of the bars 8, represented as laterally 20 separated and as connected suitably at their forward ends with the pole or tongue 9. (See Fig. 1.) When the beams 2 are elevated to lift the shovels or plows out of the ground in order to move the cultivator from place to 25 place or for any other reason, the arch hereinbefore described and illustrated as composed of the bars 4 will be correspondingly elevated, so as to engage or substantially engage the seat-supporting bars 8. In case the cultivator is to be moved any great distance and in 30 case the bars 4 do not engage the bars 8 the turnbuckle 6 can be manipulated to cause the former to engage the latter, so as to hold the

beams 2 positively against sidewise motion. In this way the plows or shovels cannot knock 35 out any of the spokes of the wheels or cause other injury.

Having thus described my invention, what I claim is—

1. In a cultivator-arch, a pair of bars 40 flexibly connected at their upper ends and diverging away from each other toward their lower ends, the latter being adapted for connection with cultivator - beams, rods connected with the bars between their place of juncture and their 45 lower ends, said rods having respectively right and left threads, and a nut, also having right and left threads, to engage the corresponding threads of said rods.

2. In a cultivator-arch, two hingedly-connected bars, adapted for connection with the beams of a cultivator, rods connected with the bars between their joint and the place at which they are connected with said beams, said rods having their inner ends provided with right 55 and left threads, and a right and left threaded nut to engage the corresponding threaded portions of the rods.

In testimony whereof I have hereunto set my hand in presence of two subscribing witnesses.

ROBERT L. HARPER.
